UNITED STATES PATENT OFFICE.

EDGAR MORTON BENHAM, OF CINCINNATI, OHIO, ASSIGNOR TO BANKER'S DUST-PROOF TIME LOCK COMPANY, OF CINCINNATI, OHIO, A PARTNERSHIP.

TIME-LOCK.

939,384.

Specification of Letters Patent.

Patented Nov. 9, 1909.

Application filed April 22, 1907. Serial No. 369,615.

To all whom it may concern:

Be it known that I, EDGAR MORTON BENHAM, a citizen of the United States, residing at Cincinnati, in the county of Hamilton and State of Ohio, have invented new and useful Improvements in Time-Locks, of which the following is a specification.

My invention relates to mechanical means for automatically retracting the bolts of safes. Such mechanisms comprise some form of watch movement and means, actuated by that movement at a predetermined time to release the bolts, or usually in practice to actuate another mechanism, such as described and claimed in my application for Letters Patent Serial Number 360,137 filed March 2nd, 1907, called a device for retracting safe bolts. So-called time-locks of this class are, to avoid locking out if one movement fails, usually made with a plurality of movements and attendant throwing means, each and all of which are adapted to operate a single means for retracting the bolts or intermediate device. It is important therefore that the single retracting means should be free to operate whenever acted upon by any one or more of the movements, without interference from any non-acting movement and with the least expenditure of force. This my invention provides for, as will hereafter appear. As the relative power delivered by any mechanisms (perfection of material and workmanship being equal) will always depend upon the number of parts and the simplicity of their arrangement; I have employed a less number of parts and a simplified arrangement conducing to greater certainty and efficiency in operation. Wear and efficiency both depend largely in such delicate mechanisms, upon their being kept free from dust and dirt. To this end, I not only inclose the device as a whole in a substantial case, but each movement and all its attendant mechanism has all its working parts completely inclosed in a dust-proof receptacle, the body of which is unitary. A crystal covers the movement and discloses it to view. I place each such movement and mechanism in a separate receptacle, and the means within the device for casting the bolts is so formed and placed that any receptacle with its contents and attachments may be removed with-

out removing or affecting any other portion of the time-lock. As each receptacle with 55 contents and attachments is the duplicate of every other, they are interchangeable.

In my invention a dial, a smooth edged disk, is rotatively attached to the arbor of the spring and when the spring is wound, 60 the dial turns and the characters on its face register the amount of winding of the spring, one full rotation of the dial effecting a full winding of the spring; there are no loose parts to be re-set and each dial is 65 wound independently of all others. A stud on the under side of the dial does the tripping and also operates as a stop to prevent the movement from injury by being wound beyond capacity of the spring. 70

The advantages enumerated above, result in a more simple and complete lock, that is easier to handle, more durable, and requires less attention than any other; and no alteration of the position of the safe, nor jarring 75 upon it, will affect my time lock. Like other such locks it is wound and set before closing, and when closed there is no means of communication therewith from the outside.

My invention is illustrated in the accompanying drawings, in which:

Figure 1, is a front view in perspective, of my improved time lock complete, with the door of the case open. Fig. 2, is a top plan view of the empty, open case, with hinged 85 cover broken away. Fig. 3, is a top plan view of one empty receptacle, with actuating lever and crystal in position. Fig. 4, is an under plan view of an empty receptacle. Fig. 5, is the cap that covers the back of 90 movement, to hold it in the receptacle. Fig. 6, is an enlarged view in side elevation, of a receptacle and attached spring case and pointer;—with one corner of the receptacle in section to show one of the cushioned 95 threaded posts. Fig. 7, is the same as Fig. 6, with the receptacle and main spring in section, and the gears connecting the movement and winding arbor exposed, with other portions of the movement, the cushioned 100 posts, etc. omitted. Fig. 8, is an under plan view of the winding arbor, showing the hooked stud and the gear that meshes with the movement gear. Fig. 9, is a top plan view of the same showing the double ratchet. 105 Fig. 10, is a side elevation of the winding

arbor, showing the hooked stud; and the gears and sleeve on said arbor, in section. Fig. 11, is the inner end of the spring.

Referring to the drawings, A represents the case, usually made of metal and adapted to hold the several receptacles B, each of which contains complete means for shifting the bar C. The case A is preferably as nearly dust proof as possible, and is shown with a door A¹ any suitable portion of which is a glass a, so that the operation of all movements can be observed without opening the door. The case is adapted to be secured at the back to a safe door as by bolts passing through holes a³; and the notch e in the bar C receives and controls the trigger (not shown) used to cast the bolts or operate the intermediate bolt retracting device. Any suitable opening a¹ in the case is adapted to admit the part actuated, and permit its movement by the bar C. The door A¹ may be kept closed in any convenient manner, as by the catch a².

Each receptacle B is formed from a solid block, its sides being made smooth to minimize friction, each receptacle with its contents is independent of all others and is provided with its own threaded posts b. One of these posts pierces each corner of each receptacle, and is provided with a spring s above and another s¹ below a shoulder b¹ left in the receptacle; and the springs are suitably compressed by a washer nut s² all in the usual way. The posts b are threaded into holes a⁴ in the case, which holes are preferably surrounded by recesses a⁵ in which the washer nuts s² seat. Each receptacle is provided with an opening b² adapted to receive the time movement D which is protected from above by a tight fitting glass b³; and is secured in position from below by the plate b⁴, fastened in any suitable manner as by screws that enter the holes b⁵.

The movement D is any suitable watch mechanism with the main spring and barrel omitted. The only portion of the movement that needs illustration or description is the gear d, pinion d¹, and the suitably journaled shaft d² to which they are rotatively attached. The gear d meshes with escapement mechanism of a usual type (not shown); and the pinion d¹ meshes with the gear e which is loose on the main spring arbor E. When gear e is brass, the pinion is preferably of a dissimilar metal, as steel, to insure long life in the mechanism. The arbor E is journaled at the back in the spring case B¹, which is fastened to the back of the receptacle B by screws b⁶ or otherwise. Toward the front end this arbor is journaled in the front of the receptacle. The main spring e¹ is coiled within its case B¹, around the arbor E; is fastened to the case in any convenient manner as by rivet e², and has a suitable opening e³ toward

its inner end, which is adapted to be engaged by a hooked stud e⁴ fixed to the arbor E, so that rotation of the arbor in the proper direction will wind the spring. A disk e⁵, having ratchet teeth e⁶ is fixed to the arbor in any convenient way; and is shown in the drawings pinned to a sleeve e⁷, which is fixed in the arbor E, by the pin e⁸. The gear e is kept in its proper position on the arbor by the shoulder e⁹ at the rear and the sleeve e⁷ and disk e⁵, in front. The teeth e⁶ are in size and form adapted to engage any suitable number of ratchet pawls e¹⁰ secured to the gear e by screw studs e¹¹, and held against the teeth by springs e¹². It will be seen that the ratchet and loose gear e permit the main spring to be wound, but prevent its unwinding except gradually through the operation of the movement. A partition b⁷ pierced loosely by the arbor E divides the receptacle B from the spring case B¹ (see Fig. 7). It will be seen that when the mechanism is in place, the delicate working parts are not exposed to dust.

Without, and in front of the receptacle B upon the arbor E, the outer portion of which e¹⁸ is squared for contact with a key (not shown) is a disk e¹³ with any suitable means of attachment to the arbor, as the extended hub e¹⁴ pierced by the set screw e¹⁵, adapted to engage the notch e¹⁶ in the arbor. The upper surface of the dial is graduated and provided with numerals to indicate hours, and when wound a fixed pointer b⁸ indicates the number of hours from the time of winding before the mechanism will cause the dial to throw the bar C. The pointer is held in position in any ordinary way as resting at one point on the fixed rod b⁹, and at another on the sleeve b¹⁰ pierced by the screw b¹¹ threaded into the front of the receptacle. On the under side of the dial disk e¹³ is a stud e¹⁷ adapted to engage and shift a lever b¹², pivoted to the front of the receptacle by the screw stud b¹³. The movement of this lever is restricted by the studs b¹⁴; and its movement into the position shown by full lines in Fig. 1, throws the bolt mechanism, by sliding the bar C. The bar C is seated upon a raised edge a⁶ at the inner side of the case A, said case being suitably formed with a bearing surface for the bar and said bar being held in position by the screw studs c¹, which pierce the bar C through the elongated slots c². Elongated notches c³ on the inner edge of the bar C are each adapted to receive the outer end of one of the levers b¹². Any of the usual means of holding the bar until forwarded by the levers, may be employed, as the spring e⁴ in a hole in the end of the bar and a plunger c⁵ loosely seated thereon. The dotted lines in Fig. 1 show the bar in the position maintained by the plunger and spring, before it has been actuated by the levers b¹².

The operation of my time lock is as follows:—Assume that the movements have all run down. The bar C and the levers b^{12} will be in the position shown by dotted lines. 5 Place a suitable clock key over one of the arbor stems e^{18} and wind it (ordinarily to the right) until the figures on the dial e^{18} representing the number of hours from the present to the desired time of action, are directly next the end of the pointer b^8 . This 10 turn has wound the main spring e^1 , and set the watch movement and its connected mechanism in action. Each of the other movements is then wound to the same figures on 15 its dial. The case is closed, and it is understood that the trigger or actuating lever of the device for retracting safe bolts is resting in the notch c , in the position of the dotted lines, and that said device is set for action. 20 When the movements have turned the dials back to 0, each of the studs e^{17} will contact with its lever b^{12} , pressing the outer end of 25 said lever against the bar C forcing it to the left as shown in Fig. 1 to the position of full lines. The trigger of the bolt retracting device will be carried with the bar C in its movement, and said device sprung when the bar has been carried far enough.

I claim as my invention and desire to secure by Letters Patent of the United States:

1. A time-lock device embodying a watch-movement, without a motor; a rotatable arbor journaled adjacent to such movement; gears immediately connecting the two in forward movement only; and an actuating spring wound directly upon said arbor. 35

2. A time-lock device embodying in combination a watch-movement without an actuating motor; a rotatable arbor journaled adjacent thereto; an actuating spring wound upon said arbor; a ratchet-impelled gear upon said arbor and actuated thereby in one 40

direction only; said gear meshing immediately with the receiving gear upon the watch movement. 45

3. A time-lock mechanism embodying in combination a watch-movement without a motor; a rotatable arbor journaled adjacent thereto; an actuating spring wound upon the same; a fixed ratchet, a loose gear adjacent thereto upon said arbor; spring-actuated pawls upon the loose gear engaging the ratchet in one direction only, and a gear upon the watch movement meshing directly with said gear upon the spring-actuated arbor. 50

4. A time-lock device embodying in combination, a watch-movement without an actuating motor; a rotatable arbor journaled adjacent to said watch-movement; gears connecting the two immediately in forward movement only; and a graduated disk fastened upon said arbor for regulating the degree of winding with reference to a fixed pointer. 60

5. A time-lock device embodying in combination, a watch-movement without an actuating motor; a rotatable arbor journaled adjacent to said watch-movement; gears connecting the two directly in forward movement only; and a graduated disk upon said arbor for regulating the degree of winding a fixed pointer arranged with reference to the graduations upon said disk; and a stud upon said disk to engage the bolt releasing mechanism and to act as a stop limiting excessive rotation of the disk. 70

In testimony whereof I have hereunto set my hand in presence of two subscribing witnesses.
